TIE HOLDER

Harry A. Tomarin, Cincinnati, Ohio, assignor to
Leroco Industries Incorporated, Reading, Ohio,
a corporation of Ohio

Application August 27, 1946, Serial No. 693,246

4 Claims. (Cl. 211—113)

1

This invention relates to a holder, and more particularly to a holder for neckties.

An object of the invention is to provide an inexpensive, yet highly efficient tie holder for use with a standard garment hanger.

Another object of the invention is to provide preformed sheets of material which may be delivered to drycleaning establishments, and the like, in flat condition, to be folded and attached to a standard garment hanger by the cleaner at the time of use.

Another object of the invention is to provide an inexpensive tie-holder attachment for garment hangers which is adapted to hold from one to twenty-four ties in such a manner as to preclude their accidental or unintentional removal from the holder.

Still a further object of the invention is to provide a tie holder, for attachment to a garment hanger, and which is characterized by the ease with which ties are secured to and removed from said holder.

Another object of the invention is to provide a tie holder for attachment to a standard garment hanger, for providing a device for holding ties incident to the cleaning operations to which they are subjected in dry-cleaning establishments, and on which they may be delivered by the cleaner to their customers, and which may be used by the customers as a convenient, easy to use tie rack.

A further object of the invention is to provide a tie holder having the hereinabove described characteristics and which may be inexpensively manufactured in great quantities using modern mass production methods.

These and other objects are attained by the means described herein and as disclosed in the accompanying drawing, in which:

Fig. 1 is a top plan view of an extended blank comprising a detail of the invention, and from which the tie holder is formed.

Fig. 2 is a front elevation showing the blank of Fig. 1 folded and attached to a standard garment hanger, and with a necktie supported therefrom in position of use.

Fig. 3 is a sectional view on line 3—3 of Fig. 2.

Fig. 4 is a view similar to Fig. 3, but differing therefrom in that a tie is associated with each of the registering slots in flaps 26 and 28, whereas in Fig. 3 the necktie is supported by both of the registered slots of said flaps.

With reference now to Fig. 1, it will be observed that body member 10 of the hanger is substantially rectangular in shape, is defined by a pair

2

of laterally spaced, substantially parallel side edges 11, a pair of end edges 12 and has a median score line 13 extending transversely thereof between end edges 12 and intermediate and parallel with side edges 11.

Body member 10 may be fabricated from sheet material such as cardboard, metal, plastic, fabric, and the like, it being understood that the particular material selected will be determined by the particular usage to which the tie holder will be put. That is, for one time delivery use by dry cleaners, it may be desirable to fabricate the holder from cardboard; however, for home use it may be more desirable to fabricate it from metal, fabric, or of plastic.

A plurality of pairs of laterally aligned T slots, denoted generally by the numeral 15 are provided in body member 10, wherein each T slot includes an elongated horizontal portion 16 of sufficient extent to receive the neck band 20 of a necktie 22, and a throat portion 24 which is disposed at substantial right angles relative to horizontal portion 16. The lower end of said throats terminate at and form an opening in side edges 11 for facilitating the introduction of the neck band of a necktie into horizontal portion 16 of the slots.

In the preferred embodiment of the invention, the adjacent horizontal or body portions 16 of the T slots are alternately spaced at different elevations relative to side edges 11, thereby providing a compact, yet sturdy holder which will accommodate from one to twenty-four ties in such a manner that a considerable portion of each tie is always visible.

The tie holder blanks may be delivered to the users thereof in the flat, extended condition shown in Fig. 1, it being understood that body portion 10 will be folded on itself about median 13 for providing a pair of downwardly extending flaps 26 and 28. It will be observed that when thus folded to the position illustrated in Figs. 2 and 3 the slots comprising each pair will be in registry with one another, for providing a double thickness of supporting material for the neckband of a necktie, as illustrated in Fig. 3. If desired, and in order to increase the carrying capacity of a tie holder, a tie may be associated with each of the T slots comprising a pair of flaps 26 and 28, as disclosed in Fig. 4.

Neckwear, and the like, may be easily mounted in the slots by introducing the neckband portion upwardly thru throat portion 24 then into horizontal portion 16. Once a tie has been mounted in a slot, or pair of slots, as disclosed in Figs. 2 and 3, it will be noted that it cannot be acci-

dentially or unintentionally removed from the holder, since the horizontal slot portion engages the neckband of the tie at its narrowest portion. The relationship between the width of throat portion 24 to the length of horizontal portion 16 is such as to preclude removal of the tie from portion 16 except in response to an intentional and deliberate act on the part of the user of the device. The outward taper of the ends of a tie effectively precludes the tie from being pulled thru portion 16, wherefore it will be observed that the ties will be positively, though removably, secured to the tie holder. *RECORDED AND INDEXED*

The folded holder is adapted to be inserted over the lower horizontal leg 30 of a standard triangular shaped garment hanger, denoted generally by the numeral 32, in such a manner as to locate flaps 26 and 28 on opposite sides of said leg.

As disclosed in Fig. 3, the holder is positively locked onto leg 30 of the hanger when one or more ties are mounted in the slots, wherefore the tie holder is not only positively locked to the hanger, but the ties are, in turn, locked to the holder. This construction enables dry cleaners to actually clean ties while supported on my holder, thereby eliminating the current practice of having to attach small identifying tabs to each tie being cleaned. The resultant savings in time more than offsets the cost of my device.

While my holder has been primarily designed for neckties, it is admirably adapted to hold belts and other elongated articles of apparel.

It should be understood that various changes in the structural details of the present invention may be made within the scope of the claims, such as, by way of example, mounting body member 10 in such a manner as to have throat portions 14 extending upwardly from portions 15, or in inverted T formation, without departing from the spirit of the invention.

What is claimed is:

What is claimed is:

1. A holder for retaining articles of neckwear in a draped condition intermediate their length, which comprises a body member of flexible sheet material having substantially parallel side edges, a plurality of pairs of substantially T-shaped slots provided in said body portion in opposed relationship, each T slot including an elongated horizontal portion of sufficient extent to receive the neckband of a necktie and a throat portion disposed at substantial right angles thereto and opening through an adjacent side edge for the reception of the neck band of a tie incident to being introduced into the horizontal portion of said slot.

2. A tie holder for attachment to the lower horizontal leg of a standard triangular garment hanger, which holder comprises a sheet of flexible material defined by a pair of laterally spaced

substantially parallel side edges, and a pair of end edges, a median score line disposed intermediate said side edges and extending between said end edges, a pair of opposed laterally aligned T slots provided in said material with the individual slots comprising the pair located on opposite sides of said median score line and with the lower end of each T terminating at and in open communication with a side edge.

3. A tie holder for attachment to the lower horizontal leg of a standard triangular garment hanger, which holder comprises a sheet of flexible material defined by a pair of laterally spaced substantially parallel side edges, and a pair of end edges, a median score line disposed intermediate said side edges and extending between said end edges, a pair of opposed laterally aligned T slots provided in said material with the individual slots comprising the pair located on opposite sides of said median score line and with the lower end of each T terminating at and in open communication with a side edge, said sheet being foldable along said median score line for disposing corresponding portions of said holder on opposite sides of said median line and in substantial parallelism for locating said slots in register; said holder adapted to be hung from said lower hanger leg with corresponding portions of the hanger disposed on opposite sides of said leg.

4. As a new article of manufacture a tie holder attachment for the lower horizontal leg of a standard triangular garment hanger, said holder comprising a sheet of flexible material folded on itself for providing a pair of downwardly extending flaps suspended from the lower horizontal leg of a garment hanger with said flaps depending on opposite sides thereof, a plurality of T slots provided in one of said flaps with the lower end of each T terminating at and in open communication with the lower edge of said flap.

HARRY A. TOMARIN.
